UNITED STATES PATENT OFFICE

159,596

DISPENSING HOLDER FOR BOTTLES
OR THE LIKE

Edwin F. Bushman, Aurora, Ill.

Application September 13, 1948, Serial No. 148,558

Term of patent 14 years

(Cl. D58—26)

To all whom it may concern:

Be it known that I, Edwin F. Bushman, a citizen of the United States and a resident of the city of Aurora, in the county of Kane and State of Illinois, have invented a new, original, and ornamental Design for a Dispensing Holder for Bottles or the like, of which the following is a specification, reference being had to the accompanying drawing, forming a part thereof.

I claim:

The ornamental design for a dispensing holder for bottles or the like, as shown.

EDWIN F. BUSHMAN.
